UNITED STATES PATENT OFFICE

HAL FREDERICK FRUTH, OF CHICAGO, ILLINOIS, AND TERENCE ONAS WESTHAFER,
OF DOWNERS GROVE, ILLINOIS, ASSIGNORS TO WESTERN ELECTRIC COMPANY, INCORPORATED, OF NEW YORK, N. Y., A CORPORATION OF NEW YORK

TRANSMITTER

Application filed October 11, 1927. Serial No. 225,434.

This invention relates to transmitters, and more particularly to resistance varying apparatus for telephone transmitters.

The primary object of this invention is to provide a simple, economically constructed and efficiently operable resistance varying means for electrical transmitters.

In accordance with the general features of the invention one embodiment thereof comprises a telephone transmitter provided with a button which includes a back electrode assembly comprising a carbon disk clamped between an insulating cup and a metallic terminal member. Granular carbon is positioned within the cup adjacent the front electrode assembly which includes a carbon disk secured by an alloy of low melting point within a metallic cup. A bi-metallic, corrugated diaphragm comprised of metals having different coefficients of expansion centrally supports the front electrode assembly and is clamped between the insulating cup and a metallic clamping ring. The assembly of these parts presents a transmitter button having a minimum number of elements assembled in a very convenient and economical manner.

These and other objects will be apparent from the following detailed description when considered in connection with the accompanying drawings, wherein

Fig. 1 is a side elevational view disclosing an application of the invention to a commercial type of telephone transmitter, a portion thereof being shown in section to more clearly indicate structures otherwise hidden;

Fig. 2 is a central, longitudinal sectional view of the transmitter button disclosed in Fig. 1;

Fig. 3 is a view showing parts of the transmitter button in section and in separated relation, and

Fig. 4 is an enlarged fragmentary detailed sectional view of the bi-metallic diaphragm disclosed in Figs. 2 and 3.

Referring now to the drawing wherein like numerals have been employed to designate similar parts throughout the various figures, it will be observed that Fig. 1 discloses a telephone transmitter indicated generally by the

numeral 10 which is provided with the usual mouthpiece 11 threaded within a face plate 12. Secured to the rear of this face plate 12 is a metal bridge piece 14 which is provided medially thereof with a mounting member 15. A set screw 16 serves to secure a metallic shank 18 of a transmitter button indicated generally by the numeral 19 in a fixed position within the mounting member 15.

This transmitter button 19 comprises an internally threaded metal flange or terminal section 20 formed integral with the shank 18 which forms a part of the back assembly of the button 19. This back assembly also includes a carbon disk 22 clamped against the front surface of the flange 20 by means of an insulating cup 23 and forming an electrode. The cup 23 which may be constructed of a phenol condensation product, rubber or other suitable insulating material is threaded within the flange 20 and a circular recess provided in the cup serves to receive and centrally position the carbon electrode 22 as the cup is threaded into position within the flange. The forward peripheral surface of the cup 23 is threaded to receive a clamping ring 24 which serves to clamp a bi-metallic annulus or diaphragm 26 against the front surface of the cup.

This bi-metallic diaphragm 26 is provided with a plurality of annular corrugations 27 and is centrally apertured to support the front electrode assembly of the button 19 which includes a metallic cup-shaped member 28 clamped to the diaphragm 26 by means of a clamping ring 30 and a carbon disk 31 positioned within the recessed or cup-shaped portion of the member 28 to form a second electrode. To effectively and conveniently secure the carbon disk 31 within the member 28 the annular surface of the recess in the member 28 is coated with a suitable low melting point alloy 33, such as tin, solder or other suitable material, and while the alloy 33 is still molten the disk 31 is pressed into position and the alloy permitted to make a shrinking fit around the disk. By shrinking the carbon disk or electrode 31 within the member 28 which has been previously coated or

tinned, a firm mounting of the disk 31 is very conveniently effected.

A supply of granular carbon 34 placed between the carbon electrodes 22 and 31 serves to produce resistance variations in response to vibrations of the front electrode assembly. By having this diaphragm 26 of bi-metallic construction, sheets of metals having different coefficients of expansion, such as brass and another metal having a low coefficient of expansion, such as a nickel-steel alloy commonly known as "invar", a compensating effect is produced which reduces to a minimum deleterious results, such as undesirable resistance variations, which in some instances may result from temperature variations to which the transmitter is subjected. In the use of the transmitter, the temperature of the granular carbon 34, as well as of the parts associated therewith, begins to rise as soon as the telephone circuit is closed, and this rise in temperature increases the contact resistance of the granular carbon, resulting in a decrease in the current to less than its optimum value. To compensate for this decrease, the diaphragm 26 may be constructed to move inwardly toward the carbon 34 upon increase in temperature, which will increase the pressure within the carbon 34 and tend to decrease its resistance and increase the current. The diaphragm may also be so constructed as to compensate for the expansion and contraction of ring 24 and the other parts due to temperature changes, in which case the relative positions of the metals constituting the diaphragm will be dependent upon the particular arrangement of the other parts which constitute the transmitter button. The annular corrugations 27 formed in the diaphragm 26 lend sufficient rigidity thereto to enable the use of a relatively thin metallic diaphragm, and thereby introduce a decided factor of economy in metallic diaphragm construction.

The arrangement of the described apparatus is advantageous in that it presents a resistance varying apparatus, the parts of which are relatively easy to manufacture and which may be readily assembled as well as disassembled for purposes of repair or replacement, with a minimum amount of effort. Thus, for example, the carbon electrodes 22 and 31 need not be subjected to special treatment for the purpose of preparing them for copper plating, a step which is sometimes practiced when carbon electrodes are to be soldered in position instead of conveniently and removably clamped in position in accordance with the teachings of the described invention. Likewise the shrinking of the electrode 31 within the alloy 33 contained within the recess of the member 28 is a very convenient and effective way to secure material, such as carbon, in a fixed position.

The insulating cup 23 which may be readily

molded from suitable insulating material, such as phenol condensation products or the like, serves as a clamping member as well as an insulating means for separating the front and back electrode assemblies and also provides a container for the granular carbon. Thus it is to be understood that the simplicity of design and the novel arrangement of the cooperating parts constituting the described apparatus, renders possible the manufacture thereof at a minimum cost and the product produced has improved transmission characteristics.

Although the invention has been described in connection with a certain type of telephone transmitter, it is to be understood that this invention is capable of many other applications and should be limited only by the scope of the appended claims.

What is claimed is:

1. In a transmitter, a resistance varying means including a pair of electrodes, a supply of resistance material positioned therebetween, a diaphragm operatively associated with one of the electrodes comprising metallic materials having different coefficients of expansion, and a second diaphragm adapted to actuate one of the electrodes.

2. In a transmitter, a resistance varying means including a pair of electrodes, a supply of resistance material positioned therebetween, a bi-metallic diaphragm operatively associated with one of the electrodes, and a second diaphragm adapted to actuate one of the electrodes.

3. In a transmitter, a resistance varying means including a metallic member, a carbon electrode removably secured thereto and electrically connected thereto, a bi-metallic diaphragm, a carbon electrode operatively associated therewith, and an insulating member between the diaphragm and the metallic member.

4. In a transmitter, a resistance varying means including an electrode having a recess, a carbon plate fitting within said recess and substantially filling the same, and a material of low melting point interposed between the carbon plate and the walls of the recess for retaining the carbon plate within the recess.

5. In a transmitter, a vibratory member responsive to pressure variations, an electrode adapted to be vibrated thereby, a variable resistance means positioned adjacent said electrode, and supporting means for said electrode comprising a bimetallic member adapted to move the electrode toward and away from the variable resistance means in response to changes in temperature.

6. In a transmitter, a vibratory member responsive to pressure variations, an electrode adapted to be vibrated thereby, a variable resistance means positioned adjacent said electrode, and supporting means for said electrode comprising a bimetallic diaphragm

adapted to move the electrode toward and away from the variable resistance means in response to changes in temperature.

7. In a transmitter, a vibratory member responsive to pressure variations, an electrode adapted to be vibrated thereby, microphonic means associated with said electrode, and supporting means for said electrode comprising a bimetallic diaphragm constructed and arranged to tend to move the electrode toward and away from the microphonic means upon fluctuations in the temperature.
8. In a transmitter, a recessed member, a member responsive to pressure variations and adapted to actuate said recessed member, an electrode snugly seated in the recess of said recessed member and secured therein by adhesive material, and means for supporting the recessed member comprising a bimetallic temperature-responsive member having a portion thereof secured to the recessed member.

In witness whereof, we hereunto subscribe our names this 29th day of September, A. D. 25 1927.
